(57) **CLAIM**

The ornamental design for a bag dispenser, as shown and described.

DESCRIPTION

FIG. 1 is a top front perspective view of a bag dispenser, showing our new design.

FIG. 2 is a bottom rear perspective view of the bag dispenser.

FIG. 3 is a front elevational view of the bag dispenser.

FIG. 4 is a rear elevational view of the bag dispenser.

FIG. 5 is a left side elevational view of the bag dispenser.

FIG. 6 is a right side elevational view of the bag dispenser.

FIG. 7 is a top plan view of the bag dispenser; and,

FIG. 8 is a bottom plan view of the bag dispenser.

The bag dispenser is shown with symbolic breaks in its length and width. The appearance of any portion of the article between the break lines forms no part of the claimed design. Features illustrated in broken lines form no part of the claimed design.

1 Claim, 8 Drawing Sheets
